UNITED STATES PATENT OFFICE

JOSEPH FAUSSE, OF MELROSE, MASSACHUSETTS, ASSIGNOR TO THE LITTLEWAY PROCESS COMPANY, OF LYNN, MASSACHUSETTS, A CORPORATION OF MASSACHUSETTS

MEANS FOR HOLDING SHOE UPPERS IN LASTED POSITION

Application filed April 25, 1932. Serial No. 607,281.

This invention relates to means for use in the manufacture of shoes for holding the uppers in lasted position until conditions are such that no extraneous holding means is needed by reason, for example, of the setting of cement used in the lasting operation or, in lasting the toes of some kinds of shoes, by reason of the hardening of box toe stiffening material in the uppers. The invention is 5 applicable to the lasting of shoes of different kinds, including those in which the margin of the upper is lasted in substantially parallel relation to the bottom of the last over an insole or other shoe bottom part (hereinafter 10 frequently referred to generically as the "sole") and those in which it is lasted with a portion thereof in upstanding position against a lip or shoulder on the sole, and the invention is accordingly herein illustrated 15 by reference to the manufacture of shoes of both these general types. It is also illustrated particularly as applied to the lasting of toes, but it is to be understood that it is not thus limited, but is applicable, for example, to the lasting of the heel ends. 20

For holding an upper in lasted relation to a sole as above described the invention provides a device of simple and inexpensive construction adapted to be quickly and easily 25 applied in proper relation to the upper and fastened in upper-holding position and to be thereafter readily removed from the shoe. In the illustrated embodiment of the invention this device comprises a substantially U-shaped upper-holding member formed to extend around an end of the shoe bottom over the margin of the sole, and another member, which may be termed an intermediate member, arranged to extend over the sole in engagement with the upper-holding member at 30 the opposite sides of the shoe bottom to press it toward the bottom of the last and constructed for attachment to the shoe to maintain the upper-holding member in upper- 35 holding position, the intermediate member being so formed as to leave visible the greater portion of the shoe bottom located near the margin of the sole along the upper-holding member to facilitate the positioning of the 40 device in proper relation to the shoe ma- 45

terials. In the construction shown the upper-holding member is angular in cross section to provide a portion arranged to face the bottom of the last in pressure-applying relation to the upper and also an upstanding portion or flange, so that the member may be conveniently positioned and pressed upon the upper by use of the wipers of a lasting machine, and the intermediate member acts by engagement with the upstanding flange to 50 maintain the upper-holding member in proper position. As further herein shown, in accordance with one feature of the invention, the intermediate member is connected to the upstanding flange of the upper-holding member so that both members may be conveniently handled as a unit, the drawing illustrating, by alternative constructions, different ways of connecting the two members at the opposite sides of the shoe bottom 55 and also showing intermediate members of different forms. Both members may be conveniently and inexpensively made of sheet metal, and preferably the intermediate member will be provided with a plurality of openings, as illustrated, through which fastenings such as tacks may be driven through the sole and into the last to fasten the device on the shoe with pressure directed toward the bottom face of the last. In a further novel 60 aspect also the intermediate member, in one form illustrated, has a resilient portion adapted to be sprung toward the bottom face of the last by the fastening means for better insurance that the device will be held by the 65 fastening means in such manner as to maintain adequate pressure upon the upper. 70

The above and other features of the invention, including various novel details of construction and combinations of parts, will 80 now be more particularly described by reference to the accompanying drawing and pointed out in the claims. 85

In the drawing,

Fig. 1 is a perspective view illustrating 90 the manner of applying to the toe of a shoe an upper-holding device constructed in accordance with this invention by the aid of the toe-embracing wipers of a bed-lasting machine, the shoe shown being one of that type 100.

in which the margin of the upper is lasted inwardly over an insole in generally parallel relation to the last bottom;

Fig. 2 is a perspective view of the forepart 5 of the shoe with the upper-holding device in position thereon, illustrating more clearly the construction of the device;

Fig. 3 is a sectional view of the device on the line III—III of Fig. 2;

10 Fig. 4 is a perspective view of the forepart of a shoe with an alternative form of upper-holding device applied to the toe end thereof;

Fig. 5 is a longitudinal section through the shoe and the upper-holding device shown in 15 Fig. 4; and

Fig. 6 is a perspective view illustrating the use of an upper-holding device of the form shown in Figs. 4 and 5 for holding the toe end of the upper of a shoe having an in- 20 sole provided with a lip against which a portion of the margin of the upper is lasted in upstanding position.

In both forms illustrated the upper-holding device includes a substantially U-shaped 25 upper-holding member 10 which may be conveniently made of sheet metal and is constructed to extend around the toe end of the shoe bottom in engagement with the upper over the margin of the sole, the member thus 30 having arms that are spaced from each other laterally of the shoe for holding the upper along the sides of the shoe bottom. In the construction shown the member 10 is angular in cross section to provide an upper-engaging 35 portion 12 arranged to face the bottom of the last in substantially parallel relation thereto and an upstanding portion or flange 14 in angular relation to the portion 12, the flange 14 extending outwardly over the portion 12 of 40 the member and forming an acute angle therewith. The member thus formed is adapted to be conveniently applied to a shoe by the aid of the toe-embracing wipers 16 (Fig. 1) of a bed-lasting machine such as 45 commonly used in lasting the toes of shoes, the wipers engaging the upstanding flange 14 to position the member in proper relation to the shoe, and it may be also to force it somewhat rearwardly over the shoe bottom, 50 and engaging the portion 12 of the member to press it firmly down upon the upper. The upstanding flange 14 further assists in rendering the member 10 substantially inflexible in directions heightwise of the shoe, and its 55 outwardly inclined relation to the portion 12 is of particular advantage in lasting the toe of a shoe in which a portion of the margin of the upper is held in upstanding position against a lip or shoulder on the sole, such as 60 a welt shoe, since ample room is afforded for the gathers or folds in the upstanding margin of the upper around the end of the toe.

For engaging the upper-holding member 10 to maintain it in pressure-applying relation to the upper there is provided, in the

form of device shown in Figs. 1, 2 and 3, an intermediate member or plate 18 which may also be conveniently formed of sheet metal, this plate having arms 20 arranged to extend laterally of the shoe over the sole with similarly extending projections 22 (Fig. 3) at their ends lying in openings or slots formed in the upstanding flange 14 at the opposite sides of the shoe bottom in locations substantially midway between the front and rear ends of the member 10. In this manner the plate 18 is interlocked with the member 10 so that both members may be conveniently handled as a unit. It will be evident that the plate 18 is thus positioned at a substantial distance above the bottom face of the sole, and it is so formed as to leave visible, for the most part, the portions of the shoe bottom that are located near the margin of the sole around the toe so as to facilitate the positioning of the device in proper relation to the shoe materials. To maintain the device in operative position any suitable fastening means acting on the plate 18 may be utilized, the drawing illustrating the use of tacks 70 inserted in openings provided in the plate and driven through the sole and into the last in such manner as to clamp the device down upon the shoe bottom by their heads. The plate 18 in the construction shown is provided with an arm 24 extending rearwardly lengthwise of the shoe substantially midway between the opposite side edges of the shoe bottom and with another arm 26 extending forwardly toward the toe end of the shoe, each arm having an opening herein 75 at its end to receive a tack. Preferably the plate 18 is formed of spring metal, so that the arms 24 and 26 may be sprung somewhat downwardly toward the sole by the tacks to assist in insuring adequate holding pressure on the member 10. The two arms 24 and 26 are also inclined somewhat downwardly toward the shoe bottom to bring their tack-receiving ends nearer the sole and thus to 80 permit the tacks to be driven farther into the last. As illustrated also additional openings 28 are provided in the intermediate portion of the plate 18 through one or more of which a tack or tacks may be driven if desired. It will be evident that with the plate 18 fastened as illustrated the pressures applied by the plate to the member 10 are substantially equalized at the opposite sides of the shoe bottom, and since the plate is connected to the member 10 in locations substantially or approximately midway between the front and rear ends of the member, the pressures applied to the upper by the member at its front and rear end portions are also substantially equalized.

In the alternative construction illustrated in Figs. 4 and 5 there are provided in the upper edge portion of the flange 10 at the opposite sides of the device recesses or open-

ings 30 into which extend lateral projections or arms 32 of an intermediate plate 34, and on these lateral projections are formed down-turned lugs 36 which are also turned inwardly toward each other for interlocking engagement with the outer side of the outwardly projecting flange 14. The plate 34 has several openings therein to receive tacks ^t driven into the shoe bottom as illustrated, 10 and the recesses 30 in the flange 10 are so formed that the rearwardly extending portion or arm of the plate is inclined downwardly toward the sole to permit the rear-most tacks to be driven farther into the last, 15 although not extending downwardly far enough to engage the sole. It will be understood that the tacks are driven inwardly far enough for their heads to engage the plate 34 and thus to clamp the device down upon 20 the shoe bottom with substantial pressure upon the marginal portion of the upper. The number of the tack-receiving openings in the plate 34 and their locations may be varied as desired, and this is true also of the 25 openings provided in the plate 18 of the device shown in Figs. 1, 2 and 3. It will be observed that the plate 34 is so formed and arranged as to leave visible most of the shoe bottom near the margin of the sole around 30 the toe, similarly to the construction first above described.

In Fig. 6 the form of upper-holding device shown in Figs. 4 and 5 is illustrated as applied to a shoe in which a portion of the 35 margin of the upper is lasted in upstanding position against a lip on an insole, the shoe there shown being one of the welt type. It will be observed that in this use of the device the upper-holding member presses the 40 upper closely in the angle between the feather and the lip of the insole and that the laterally projecting arms 32 of the plate 34 extend over the lip, since these arms are spaced a substantial distance above the shoe bottom. 45 The rearwardly inclined portion of the plate 34 is, moreover, narrow enough to lie between portions of the lip located at the opposite sides of the shoe bottom, so that it does not interfere with the lip. It will be further 50 understood that the form of device illustrated in Figs. 1, 2 and 3 may likewise be used on a shoe of the type shown in Fig. 6.

In the use of either of the alternative constructions described in lasting with cement 55 the toe end of a shoe of the type in which the marginal portion of the upper is lasted in substantially parallel relation to the bottom face of the last the operator may, in accordance with the usual present practice, 60 first wipe the marginal portion of the upper materials around the toe inwardly over the sole and then withdraw the wipers substantially to the edge of the shoe bottom and trim the lining and the toe box back substantially or nearly to the edge of the sole, 65

thereafter applying cement to the margin of the upper around the toe. After then advancing and closing the wipers a second time to wipe the upper over the sole, the operator withdraws them substantially to the edge 70 of the shoe bottom and places the upper-holding device upon the upper, thereafter again advancing and closing the wipers in the angle between the portion 12 and the flange 14 of the upper-holding member 10. By pressure 75 of the edges of the wipers against the flange 14 he locates the upper-holding device in proper relation to the shoe and may move it somewhat rearwardly lengthwise of the shoe in wiping engagement with the upper, 80 and by downward pressure of the wipers upon the portion 12 of the device, effected by the usual treadle with which bed-lasting machines are provided, he forces the device firmly down upon the shoe bottom. While 85 holding the device thus pressed against the shoe the operator drives tacks through one or more of the openings provided in the intermediate plate 18 or 34 to fasten the device firmly in upper-holding position, thereafter withdrawing the wipers from the shoe. The upper-holding device is then permitted to remain on the shoe, after the removal of the latter from the machine, until the cement has set, after which it is removed from the 90 shoe by inserting a suitable tool under the plate 18 or 34 and prying the device upwardly from the shoe bottom.

In lasting the toe of a shoe in which the sole member is provided with an upstanding lip, as shown in Fig. 6, the upper-holding device is applied and fastened to the shoe in substantially the same manner as above described. It will be understood, however, that the character of the lasting operations 100 performed before the device is applied will vary in accordance with the character of the shoe as well as in accordance with the preferences of different manufacturers. In 105 lasting the toe of a welt shoe, for example, the upper, lining and box toe stiffener may, in accordance with the usual practice, all be wiped inwardly and shaped by the wipers in the angle between the feather and the lip of the insole, after which the upper-holding 110 device will be applied over these parts, the box toe stiffening material being depended upon, after hardening, to maintain the toe 115 portion of the upper in lasted position when the upper-holding device is removed.

While Fig. 1 shows a shoe in which the heel-end portion of the upper is lasted with tacks, it will be understood that this end of the upper may likewise be lasted with cement, as is sometimes the practice, and that an upper-holding device constructed substantially as shown may likewise be applied and fastened to the heel end of the shoe in the same manner as at the toe end to hold the upper until the cement has set.

Having described the invention, what I claim as new and desire to secure by Letters Patent of the United States is:

- 5 1. A device for holding an end portion of an upper in lasted relation to a sole on a last, said device comprising an upper-holding member formed to extend around an end of the shoe bottom over the margin of the sole and having arms spaced from each other laterally of the shoe to hold the upper at the sides of the shoe bottom, and another member constructed to extend over the shoe bottom and to act on said arms to press the upper-holding member toward the bottom of the last, said other member being so formed 10 as to leave visible the greater portion of the shoe bottom located near the margin of the sole along the upper-holding member.
- 15 2. A device for holding an end portion of an upper in lasted relation to a sole on a last, said device comprising an upper-holding member formed to extend around an end of the shoe bottom over the margin of the sole and having arms spaced from each other laterally of the shoe to hold the upper at the sides of the shoe bottom, and another member constructed to extend over the shoe bottom and to act on said arms to press the upper-holding member toward the bottom of the last, said other member being so formed 20 as to leave visible the greater portion of the shoe bottom located near the margin of the sole along the upper-holding member and having one or more openings therein to receive fastening means driven into the shoe bottom to fasten it to the shoe.
- 25 3. A device for holding an end portion of an upper in lasted relation to a sole on a last, said device comprising an upper-holding member formed to extend around an end of the shoe bottom over the margin of the sole and having arms spaced from each other laterally of the shoe to hold the upper at the sides of the shoe bottom, and another member constructed to extend over the shoe bottom in engagement with said arms in locations substantially midway between their opposite ends and so formed as to leave visible the greater portion of the shoe bottom 30 located near the margin of the sole along the upper-holding member, said other member being constructed for attachment to the shoe by fastening means penetrating the sole to maintain the upper-holding member in operative position with pressure directed toward the bottom face of the last.
- 35 4. A device for holding an end portion of an upper in lasted relation to a sole on a last, said device comprising a substantially U-shaped upper-holding member formed to extend around an end of the shoe bottom over the margin of the sole and having arms arranged to extend laterally of the shoe in engagement with said upper-holding member at the opposite sides

of the shoe bottom to press the upper-holding member toward the bottom of the last and having also an arm arranged to extend lengthwise of the shoe substantially midway between the opposite side edges of the shoe bottom and constructed for attachment to the shoe to maintain the upper-holding member under pressure toward the bottom of the last.

5. A device for holding an end portion of an upper in lasted relation to a sole on a last, said device comprising a substantially U-shaped upper-holding member formed to extend around an end of the shoe bottom over the margin of the sole, and another member having arms arranged to extend laterally of the shoe in engagement with said upper-holding member at the opposite sides of the shoe bottom to press the upper-holding member toward the bottom of the last and having also an arm arranged to extend lengthwise of the shoe substantially midway between the opposite side edges of the shoe bottom and provided with one or more openings therein to receive fastening means penetrating the sole to fasten the device on the shoe with pressure directed toward the bottom of the last.

6. A device for holding an end portion of an upper in lasted relation to a sole on a last, said device comprising a substantially U-shaped upper-holding member formed to extend around an end of the shoe bottom over the margin of the sole, and a resilient plate arranged to act on said upper-holding member at the opposite sides of the shoe bottom and to be sprung toward the bottom face of the last to maintain the upper-holding member under pressure toward the bottom of the last.

7. A device for holding an end portion of an upper in lasted relation to a sole on a last, said device comprising a substantially U-shaped upper-holding member formed to extend around an end of the shoe bottom over the margin of the sole, and another member arranged to engage said upper-holding member at the opposite sides of the shoe bottom and having a resilient portion arranged to be sprung toward the bottom of the last by fastening means penetrating the sole to maintain the upper-holding member under pressure toward the bottom of the last.

8. A device for holding an end portion of an upper in lasted relation to a sole on a last, said device comprising an upper-holding portion formed to extend around an end of the shoe bottom over the margin of the sole and having upper-holding arms spaced from each other laterally of the shoe and substantially inflexible heightwise of the shoe, and an intermediate portion arranged to extend over the shoe bottom and connected to said arms to press them toward the

bottom of the last, said intermediate portion being so constructed as to leave visible the greater portion of the shoe bottom located near the margin of the sole along the arms.

5 9. A device for holding an end portion of an upper in lasted relation to a sole on a last, said device comprising an upper-holding portion formed to extend around an end of the shoe bottom over the margin of the sole and having upper-holding arms spaced from each other laterally of the shoe and substantially inflexible heightwise of the shoe, and an intermediate portion connected to said arms and constructed for attachment to the shoe by fastening means penetrating the sole to press the arms toward the bottom of the last, said intermediate portion being so constructed as to leave visible the greater portion of the shoe bottom located near the margin of the sole along the arms.

10 10. A device for holding an end portion of an upper in lasted relation to a sole on a last, said device comprising an upper-engaging portion formed to extend around an end of the shoe bottom, and an intermediate portion connected to said upper-engaging portion in locations substantially midway between the front and rear ends of the latter at the opposite sides of the shoe bottom and constructed for attachment to the shoe by fastening means penetrating the sole to maintain the device in upper-holding position.

15 11. A device for holding an end portion of an upper in lasted relation to a sole on a last, said device comprising an upper-engaging portion formed to extend around an end of the shoe bottom, and an intermediate portion connected to said upper-engaging portion between the front and rear ends of the latter and having an arm arranged to extend lengthwise of the shoe and provided with an opening to receive a fastening driven into the shoe bottom to maintain the device in upper-holding position.

20 12. A device for holding an end portion of an upper in lasted relation to a sole on a last, said device comprising an upper-engaging portion formed to extend around an end of the shoe bottom, and a resilient intermediate portion connected to said upper-holding portion in locations at the opposite sides of the shoe bottom and arranged to be sprung toward the bottom of the last by a fastening driven through the sole and into the last to maintain the device in upper-holding position.

25 13. A device for holding an end portion of an upper in lasted relation to a sole on a last, said device comprising an upper-engaging portion formed to extend around an end of the shoe bottom, and an intermediate portion connected to said upper-holding portion in locations at the opposite sides of the shoe bottom and inclined toward the bottom

30 face of the sole for attachment to the shoe by a fastening driven through the sole and into the last.

35 14. A device for holding an end portion of an upper in lasted relation to a sole on a last, said device comprising a substantially U-shaped upper-holding member formed to extend around an end of the shoe bottom over the margin of the sole, and another member connected to said upper-holding member in locations substantially midway between the front and rear ends of the latter at the opposite sides of the shoe bottom and constructed for attachment to the shoe by fastening means penetrating the sole to maintain the upper-holding member in upper-holding position.

40 15. A device for holding an end portion of an upper in lasted relation to a sole on a last, said device comprising an upper-holding member formed to extend around an end of the shoe bottom over the margin of the sole and substantially inflexible heightwise of the shoe, and another member having arms arranged to extend laterally of the shoe and connected to said upper-holding member at the opposite sides of the shoe bottom and having also an arm arranged to extend lengthwise of the shoe and provided with an opening to receive a fastening driven into the shoe bottom to maintain the upper-holding member in upper-holding position.

45 16. A device for holding an end portion of an upper in lasted relation to a sole on a last, said device comprising an upper-holding member formed to extend around an end of the shoe bottom over the margin of the sole, and another member arranged to extend over the sole in engagement with said upper-holding member in locations between the front and rear ends of the latter at the opposite sides of the shoe bottom and having forwardly and rearwardly extending arms each provided with an opening to receive a fastening driven into the shoe bottom to maintain the upper-holding member in upper-holding position.

50 17. A device for holding an end portion of an upper in lasted relation to a sole on a last, said device comprising a substantially U-shaped upper-holding member formed to extend around an end of the shoe bottom over the margin of the sole and substantially inflexible heightwise of the shoe, and another member having projections extending laterally of the shoe into openings in said upper-holding member at the opposite side of the shoe bottom to connect the two members together, said other member being constructed for attachment to the shoe by fastening means penetrating the sole to press the upper-holding member toward the bottom of the last.

55 18. A device for holding an end portion of an upper in lasted relation to a sole on a

last, said device comprising an upper-holding member formed to extend around an end of the shoe bottom over the margin of the sole and having a portion arranged to face the bottom of the last in engagement with the upper and an upstanding portion in angular relation to said upper-engaging portion, and another member arranged to extend over the sole in engagement with said upstanding portion at the opposite sides of the shoe bottom and constructed for attachment to the shoe to maintain the upper-holding member under pressure toward the bottom of the last.

15 19. A device for holding an end portion of an upper in lasted relation to a sole on a last, said device comprising an upper-holding member formed to extend around an end of the shoe bottom over the margin of the sole and having a portion arranged to face the bottom of the last in engagement with the upper and an upstanding portion in angular relation to said upper-engaging portion, and another member arranged to extend over the sole in engagement with said upstanding portion at the opposite sides of the shoe bottom and having one or more openings therein to receive fastening means penetrating the sole to maintain the upper-holding member under pressure toward the bottom of the last.

20 20. A device for holding an end portion of an upper in lasted relation to a sole on a last, said device comprising an upper-holding member formed to extend around an end of the shoe bottom over the margin of the sole and having a portion arranged to face the bottom of the last in engagement with the upper and an upstanding portion in angular relation to said upper-engaging portion, and another member arranged to extend over the sole in interlocking relation to said upstanding portion in locations between the front and rear ends of the upper-holding member and constructed for attachment to the shoe to maintain the upper-holding member in upper-holding position.

25 21. A device for holding an end portion of an upper in lasted relation to a sole on a last, said device comprising an upper-holding member formed to extend around an end of the shoe bottom over the margin of the sole and having a portion arranged to face the bottom of the last in engagement with the upper and an upstanding portion in angular relation to said upper-engaging portion, and another member arranged to extend over the sole and having projections located in openings formed in said upstanding portion to connect the two members together, said other member being constructed for attachment to the shoe by fastening means penetrating the sole to maintain the device under pressure toward the bottom of the last.

30 22. A device for holding an end portion of

an upper in lasted relation to a sole on a last, said device comprising an upper-holding member formed to extend around an end of the shoe bottom over the margin of the sole and having a portion arranged to face the bottom of the last in engagement with the upper and an upstanding portion in angular relation to said upper-engaging portion, and another member arranged to extend over the sole and provided with lugs in angular relation thereto interlocked with said upstanding portion at the opposite sides of the shoe bottom, said other member being constructed for attachment to the shoe by fastening means penetrating the sole.

35 23. A device for holding an end portion of an upper in lasted relation to a sole on a last, said device comprising an upper-holding member formed to extend around an end of the shoe bottom over the margin of the sole and having a portion arranged to face the bottom of the last in engagement with the upper and an upstanding portion in angular relation to said upper-engaging portion, and another member of spring metal arranged to extend over the sole in engagement with said upstanding portion at the opposite sides of the shoe bottom and to be sprung toward the bottom of the last by a fastening driven through the sole and into the last to maintain the upper-holding member under pressure toward the bottom of the last.

40 24. A device for holding an end portion of an upper in lasted relation to a sole on a last, said device comprising an upper-holding member formed to extend around an end of the shoe bottom over the margin of the sole and having a portion arranged to face the bottom of the last in engagement with the upper and an upstanding portion in angular relation to said upper-engaging portion, and another member arranged to extend over the sole in engagement with said upstanding portion at the opposite sides of the shoe bottom and having an arm inclined toward the bottom face of the sole and provided with one or more openings to receive fastening means driven through the sole and into the last to maintain the device in upper-holding position.

45 25. A device for holding an end portion of an upper in lasted relation to a sole on a last, said device comprising a substantially U-shaped upper-holding member of sheet metal formed to extend around an end of the shoe bottom over the margin of the sole and angular in cross section to provide an upper-engaging portion in substantially parallel relation to the bottom of the last and an upstanding flange, and a plate arranged to extend over the sole in engagement with said upstanding flange at the opposite sides of the shoe bottom and constructed for attachment to the shoe by fastening means penetrating

- the sole to maintain the upper-holding member in upper-holding position.
26. A device for holding an end portion of an upper in lasted relation to a sole on a last, said device comprising a substantially U-shaped upper-holding member of sheet metal formed to extend around an end of the shoe bottom over the margin of the sole and angular in cross section to provide an upper-engaging portion in substantially parallel relation to the bottom of the last and an upstanding flange, and another member in interlocking engagement with portions of said flange located at the opposite sides of the shoe bottom between the front and rear ends of the upper-holding member and constructed for attachment to the shoe to maintain the upper-holding member in upper-holding position.
27. A device for holding an end portion of an upper in lasted relation to a sole on a last, said device comprising an upper-holding member of sheet metal formed to extend around an end of the shoe bottom over the margin of the sole and angular in cross section to provide an upper-engaging portion in substantially parallel relation to the bottom of the last and an upstanding flange, and another member arranged to extend over the sole and having downturned lugs for engaging said upstanding flange on its outer side at the opposite sides of the shoe bottom, said other member being constructed for attachment to the shoe by fastening means penetrating the sole to maintain the upper-holding member in upper-holding position.
28. A device for holding an end portion of an upper in lasted relation to a sole on a last, said device comprising a substantially U-shaped upper-holding member of sheet metal formed to extend around an end of the shoe bottom over the margin of the sole and angular in cross section to provide an upper-engaging portion in substantially parallel relation to the bottom of the last and an upstanding flange, said upstanding flange having recesses in its upper edge, and a plate having projections arranged to extend into said recesses and provided with downturned lugs for engaging the outer side of the flange, said plate being constructed for attachment to the shoe to maintain the upper-holding member in upper-holding position.
29. A device for holding an end portion of an upper in lasted relation to a sole on a last, said device comprising an upper-holding member of sheet metal formed to extend around an end of the shoe bottom over the margin of the sole and angular in cross section to provide an upper-engaging portion in substantially parallel relation to the bottom of the last and an upstanding flange, said upstanding flange having recesses in its upper edge in portions thereof that extend along the opposite sides of the shoe bottom, and a plate constructed to interlock with the flange

in said recesses and having a rearwardly extending portion inclined toward the sole and provided with one or more openings to receive fastening means driven through the sole and into the last to hold the device on the shoe.

30. A device for holding an end portion of an upper in lasted relation to a sole on a last, said device comprising an upper-holding member of sheet metal formed to extend around an end of the shoe bottom over the margin of the sole and angular in cross section to provide an upper-engaging portion in substantially parallel relation to the bottom of the last and an upstanding flange inclined outwardly over said upper-engaging portion, and another member provided with downturned lugs inwardly inclined for engagement with the outer face of said upstanding flange at the opposite sides of the shoe bottom, said other member having one or more openings therein to receive fastening means driven into the shoe bottom to hold the device on the shoe.

In testimony whereof I have signed my name to this specification.

JOSEPH FAUSSE.
